(57) **CLAIM**

The ornamental design for a center console pet car seat, as shown and described.

DESCRIPTION

FIG. 1 is a front, right, top perspective view of a center console pet car seat, showing my new design;

FIG. 2 is a rear, left, bottom perspective view thereof;

FIG. 3 is a front, right, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The dashed broken lines in the figures are for the purposes of illustrating portions of the center console pet car seat that form no part of the claimed design.

1 Claim, 9 Drawing Sheets
